(No Model.)

L. K. STRANG.

LOCK.

No. 392,646.

Patented Nov. 13, 1888.

UNITED STATES PATENT OFFICE.

LEW K. STRANG, OF HAVERHILL, MASSACHUSETTS, ASSIGNOR TO HIMSELF
AND GEORGE W. HAM, OF SAME PLACE.

LOCK.

SPECIFICATION forming part of Letters Patent No. 392,646, dated November 13, 1888.

Application filed July 2, 1888. Serial No. 278,743. (No model.)

To all whom it may concern:

Be it known that I, LEW K. STRANG, of Haverhill, in the county of Essex, State of Massachusetts, have invented a certain new and useful Improvement in Locks, of which the following is a description sufficiently full, clear, and exact to enable any person skilled in the art or science to which said invention appertains to make and use the same, reference being had to the accompanying drawings, forming part of this specification, in which—

Figure 1 is a side elevation of a portion of a freight-car door, showing my improved lock in use; Fig. 2, a vertical transverse section taken on line xx in Fig. 1; Fig. 3, a front view of a portion of the escutcheon, showing the bolt removed; Fig. 4, a side elevation of the locking-bar detached; and Fig. 5, an elevation of a portion of the body of the car, showing the receiving-plate.

Like letters and figures of reference indicate corresponding parts in the different figures of the drawings.

My invention relates to that class of locks which are employed for locking freight-cars and adapted to be sealed; and it consists in certain novel features, as hereinafter fully set forth and claimed, the object being to produce a simpler, cheaper, and more effective device of this character than is now in ordinary use.

In the drawings, A represents the body of the car; B, the car-door; C, the face-plate or escutcheon; D, the bolt; E, the locking-bar, and G the catch. The door slides in ways on the outside of the car-body, in the usual manner. The escutcheon consists of a metallic plate secured to the outer face of the door B, near the rear end thereof, by means of screws z . Projecting centrally from the rear of the escutcheon is a tube, v , which passes through a hole formed in the door to receive it, the bolt D being fitted to slide in said tube.

The catch G (see Fig. 5) is secured to the edge of the door in such a position that the hole b in said plate will register with the tube v and receive the bolt D when the door is closed.

The bolt D is provided on its inner end with a head, f , which is of greater diameter than the body d of said bolt, the tube v being pro-

vided at its forward end with a flange, g , (see Fig. 3,) adapted to engage said head and prevent the bolt from being withdrawn from the tube. The body d of the bolt D is provided with three longitudinal splines, 15, 25, and 35, all disposed in the same vertical plane.

An arm or bracket, H, (see Fig. 1,) is secured to the face of the escutcheon, said arm being provided in its outer end with a hole, m , having a spline-slot, p , in its upper edge adapted to receive the bolt D and its spline 15, the flange g being also provided with a slot or groove, 45, in the same relative position, through which the spline 25 may pass.

The locking-bar E consists of a metallic plate having a hole, t , in one end, and is disposed on the bolt D between the arm H and escutcheon C, said bar being provided with a slot, r , adapted to register with the spline-slots p 45 when said locking-bar is revolved 70 on said bolt.

The bar E is provided at its opposite end with a head, 55, having a hole, 65, adapted to register with a similar hole in a stud or stop, 75, on the face of the escutcheon C and receive the sealing-wire 85.

In the use of my improvement, the door being locked, as shown in Fig. 2, if it is desired to unlock the same, the locking-bar E is revolved on the bolt D until its spline-slot r 80 registers with the similar slots p and 45 in the arm H and flange g , a stop, 95, being secured centrally to the upper portion of the escutcheon C, to engage the head 55 of said bar and determine this point. The bolt may then 85 be withdrawn until its head f is free from the plate G, and the space between the splines 25 and 35 registers with the locking-bar, permitting said bar to be turned down into its original position against the stop 95. This unlocks 90 the door and at the same time prevents the bolt from being accidentally forced inward as the inner end of the spline 25 engages the edge of the hole t in said bar. To lock the door again the bar E is elevated until its head meets 95 the stop 95, when the spline-slots all register, as before, and the bolt may be pushed inward until the opening between the splines 15 and 25 permits said bar to be dropped downward against the stop 95. A sealing-wire, 85, is then 100

passed through the holes 65 in the head 55 of said bar and in said stop, the ends of said wire being then secured by a seal, 100, in the usual manner.

5 The outer end of the bolt D may be provided with a ring, 105, to enable it to be more readily manipulated, if desired.

It will readily be seen that when the locking-bar E is down or in engagement with the stop 75 one of the splines, 15, 25, or 35, will engage said bar and prevent the bolt from being moved in or out until said bar is elevated. Moreover, when said bar is secured to the stop 75 by the wire 85, as described, it is 15 impossible to slip said bolt by stretching the loop 110 of said wire, as may be done in many locks of this description when sealed in this manner, it being impossible to move said bolt until the head 55 of the bar E is elevated and 20 brought into contact with the stop 95.

Having thus explained my invention, what I claim is—

1. In a lock of the character described, the combination of an escutcheon provided with 25 a rearwardly-projecting tube adapted to register with the bolt-hole in a locking-plate secured to the body of the ear, an arm secured to said escutcheon and provided with a bolt-hole registering with the hole in said tube, a 30 slot in said arm opening into said bolt-hole, a slot in the mouth of said tube registering with the slot in said arm, a bolt disposed in said arm and tube and provided with longitudinal splines on its body disposed in the 35 same vertical plane and adapted to slide in said spline-slots, and a locking-bar provided with a hole in one end and disposed on said bolt between said escutcheon and arm, said 40 bar having a spline-slot adapted to register with the slots in said arm and tube and permit

said bolt to be moved therein, substantially as set forth.

2. In a lock of the character described, the combination of the escutcheon C, provided with the tube v and flange g, having the spline-slot 45 45, the arm H, provided with the bolt-hole m and spline-slot p, the bolt D, fitted to slide in said arm and tube and provided with the head f and splines 15, 25, and 35, and the locking-bar E, having the bolt-hole t and 50 spline-slot r, said bar being disposed on the bolt between said arm and escutcheon, substantially as and for the purpose specified.

3. In a lock, the bolt D, provided with the splines 15, 25, and 35, arranged in the same 55 vertical plane, in combination with the locking-bar E, provided with the bolt-hole t and spline-slot r, said bar being disposed on said bolt and adapted to retain it in position in the lock, substantially as set forth.

4. In a lock, the combination of the escutcheon C, provided with the tube v and spline-slot 45, the arm H, secured to said escutcheon and having the bolt-hole m and spline-slot p, registering with said slot 45, the 65 bolt D, disposed in said arm and tube and having the head f and splines 15, 25, and 35, the locking-bar E, disposed on the tube between said arm and escutcheon and provided with the spline-slot r and head 55, having the wire-hole 70 70 65, and the stop 75, provided with a wire-hole adapted to register with the hole 65, by means of which said locking-bar may be secured to said stop and prevent the bolt from being slipped in said tube and arm, substantially as specified.

LEW K. STRANG.
